UNITED STATES PATENT OFFICE

2,161,240

YARN CARRIER ROD STOP MECHANISM
FOR STRAIGHT KNITTING MACHINESRudolph Anke, Reading, Pa., assignor to Textile
Machine Works, Wyoming, Pa., a corpora-
tion of Pennsylvania

Application March 28, 1935, Serial No. 13,469

20 Claims. (Cl. 66—129)

My invention relates to stop mechanisms for limiting the inward travel of reciprocable carrier rods of full fashioned knitting machines, and particularly to stop mechanisms for controlling the rods, as in plating, when the yarns are laid over a distance less than entirely across the knitting field.

Certain areas of a full fashioned knitted stocking comprise distinctive yarns, each of which is fed to the loop-forming elements by a carrier separate from the carriers of the other yarns, and mounted on a reciprocable carrier rod separate from the rods of the other carriers.

Although certain of the carriers are each employed primarily to lay the courses for one particular area of the fabric, other of the carriers are more extensively utilized, as in the case of the main silk carrier, which ordinarily lays the courses for reinforced heel tabs, following its feeding of silk to a main leg portion of a stocking from the welt to the instep.

To change the travel of the carrier rods, in the production of different portions of the stocking, hand-operated stop members are usually provided, as shown in Patent No. 1,528,358 issued to M. Zwicky, March 3, 1925, and assigned to the assignee hereof. These stop members are disposed in inoperative position during the full stroke of the carriers, while knitting the main leg portion of the stocking, and are operated, only when the carriers are employed to supply yarn for a limited width of the stocking, as in the heel tabs, during the knitting of which, the stop members are caused to coact with the carrier rods to limit the travel of the latter in predetermined sequence.

Among the objects of the invention are to avoid the objections to manual operation of stops of the above-mentioned character, to provide novel means operated by one of the rods for varying the stroke of another rod, and to render such means simple and durable in construction, economical to manufacture and effective in its operation.

With these and other objects in view, which will become apparent from the following description of the illustrative embodiment of the invention shown in the accompanying drawings, my invention resides in the novel arrangement, mechanism and means for operating the same, as hereinafter more particularly pointed out in the claims.

In the drawings:

Figure 1 is a rear elevational view of a portion

of a full fashioned knitting machine embodying the invention;

Fig. 2 is a view, taken substantially along the line 2—2 of Fig. 1;

Fig. 3 is an enlarged view of a portion of the device, taken in the direction of an arrow A of Fig. 2;

Fig. 4 is a sectional view of portions of the structure, taken substantially along the line 4—4 of Fig. 3;

Fig. 5 is a view, taken substantially along the line 5—5 of Fig. 4;

Fig. 6 is a view, taken substantially along the line 6—6 of Fig. 3, showing certain parts as related at one stage of operation;

Figs. 7 and 8 are views, similar to Fig. 6, illustrating the parts as related in a sequence of operations following the operation illustrated by the relation of parts in Fig. 6;

Fig. 7a is a view, taken substantially along the line 7a—7a of Fig. 7;

Fig. 9 is a diagram of the blank of a stocking leg, as knitted on a machine embodying the invention;

Figs. 10 to 13, inclusive, are diagrammatic views showing a sequence of operation of elements of the other figures, particularly as seen in Figs. 6, 7 and 8, together with portions of the stocking blank; and

Figs. 14, 15, 16 and 17 are enlarged sectional views taken substantially along the lines 14—14, 15—15, 16—16, 17—17, of Figs. 10, 11, 12 and 13, respectively.

Figs. 1 and 2 show parts of a Reading full fashioned stocking knitting machine embodying the mechanism and elements of the invention. For clearness, only those parts necessary for an understanding of the improvement are illustrated; the other parts and the operation thereof being well known, as fully shown and described in the "Reading" Full Fashioned Knitting Machine Catalogue, copyright 1929, and published by Textile Machine Works, Reading, Pennsylvania.

Referring to the drawings, a front rail 10, a back rail 12, a front bed 13 and a center bed 14, cooperate with supporting frame members, including center frames 15, to form a support for the operating parts of the machine. A coulier cam 16 cooperating with a pitman 17, rollers 18, a short rocker arm 19, and a long rocker arm 20, together provide means for translating rotary movement of the cam shaft into longitudinal reciprocative movement of a friction rod 22, and a connecting bar 23, Fig. 2. The rocker arms 19

and 20, pivotally connected to the pitman 17, by studs 24 and 25, are connected to supporting brackets 26 and 27, by shafts 28 and 29, respectively. The upper end of the long rocker arm 20 operates the friction rod 22, and the connecting bar 23, through a cross-head assembly C, Fig. 1. A plurality of friction boxes 30, only one of which is shown, are held in yielding engagement with the friction rod 22. These boxes coact with suitable means, such as dogs on the carrier rods 1 to 8, inclusive, to lock the rod 22 to the selected carrier rods for actuating corresponding yarn carriers, such as carriers 1b, 3b and 8b, Fig. 2, to feed the yarn to needles 32. Cock boxes 33, secured to the connecting bar 23, and slidably mounted on the cock-box bar 34, operate to slur a series of jacks 35 into engagement with sinkers 36, which place or "sink" the yarn between the needles.

End stops 37, of narrowing heads N, are employed to limit the strokes of the carriers, when it is desired to have the yarn laid across the entire knitting field. When the inward travel of the carrier rods is to be limited to a distance less than the entire width of the fabric, a center stop mechanism S, as shown in the above-mentioned Patent No. 1,528,358, is ordinarily employed. A bracket 38, of the mechanism S, is fixed to the center bed 14, by bolts 39, between two of the center frames 15. The bracket 38 supports a stop-backing member, or block 40, by means of a shaft 42. The block 40 is held, by a set screw 43, and a lock nut 44, in fixed position overhanging the carrier rod structure.

Carrier stop levers 51 to 58, inclusive, are pivotally mounted on a shaft 45 to limit the inward travel of the carriers 1 to 8, respectively. The stop levers 51, 53, 55 and 57, limit the travel of the carrier rods 1, 3, 5 and 7, to the left, and the levers 52, 54, 56 and 58 limit the movement of the rods 2, 4, 6 and 8 to the right.

Handles, such as handles 51a and 52a, Figs. 6, 7 and 8, are provided on the stop levers to facilitate manual operation thereof. Adjustable abutments, are provided to engage the stops, such as abutment screws 51b and 52b, which coact with the stops 1a and 2a of the rods 1 and 2, respectively. When the handles extend vertically upwardly, in the positions of handles 51a, 57a, 52a and 58a, indicated in Fig. 3, the corresponding stop levers are in operative position. When the handles extend vertically downwardly, in the positions of handles 53a, 55a, 54a, and 56a, indicated in Figs. 2, 3, 4 and 5, the transverse travel of the corresponding carriers will ordinarily be controlled only by the end stops of the narrowing head N. The carrier stop levers 51 to 58, inclusive, are provided with detents 62 which coact with grooves 63 of the shaft 45 to hold the stop levers in either operative or inoperative positions. The detents 62 are held in engagement with the shaft 45 by springs 64, which are retained in the stop levers by screws 65. This mechanism is of usual character, and employed in the full fashioned stocking knitting machine of the above-mentioned "Reading" catalogue.

In accordance with the invention, the usual carrier stop device is rendered capable of use with a high-speed machine, in which the operation of certain of the mechanisms is automatic. During the knitting of a full fashioned stocking leg blank L, as shown in Fig. 9, the carriers on the rods 1, 2, 7 and 8 are ordinarily employed during the formation of tabs T of the reinforced or plated heel portions H, in which case, the

stop levers 51, 52, 57 and 58 are normally operatively positioned, as shown in Fig. 3.

However, since carrier 2b on the rod 2, see Fig. 13, is normally employed as a main silk carrier, while fabricating that portion of the stocking between the welt and the ravel courses at the instep, and is employed, from the latter position to the ends of the heel tabs T, simultaneously with the carrier 8b, to plate one of the heel tabs T, it is desirable that means be provided for automatically operating the stop lever 52, when the operation of the carrier rod 2 is to be changed from that of a main silk carrier to that of a plating carrier, or from operation as a main silk carrier.

A rest member 46, fixed to the carrier rod 1, is provided for automatically changing the position of the stop lever 52, from that of Figs. 8, 13 and 17, to the position of Figs. 6, 10 and 14. A tension spring 47 is secured, at one end, to the handle 52a and, at the other end, to the stop block 38, through a bracket 48, Fig. 3. By this connection, the stop lever 52 is normally held against the side wall of the stop block 40, as shown in Figs. 6 and 10, when the carrier rod 1 is placed in operation, the latter action moving the rest member 46 from beneath the stop lever 52, while the spring 47 draws the lever 52 into its operative position for cooperation with the stop 2a to limit the travel of the carrier rod 2 to the right. The rest member 46, and a stop lift member 49, are so positioned on the carrier rods 1 and 2, respectively, that, during the normal plating movements of the rods 1 and 2, the member 46 and the member 49 do not affect the lever 52.

However, upon the completion of the plating of the heel tabs T, the carrier rod 2 is moved to its inoperative position, illustrated in Figs. 7 and 11, whereupon the member 49 engages the lower end of the lever 52, and raises the latter to the position better illustrated in Fig. 15. With the stop lever 52 thus positioned, the carrier rod 1 is next moved to the inoperative position of Fig. 12, whereupon, the member 46 and the member 49 are both positioned beneath the stop lever 52, see Figs. 12 and 16. With the member 46 thus positioned, the carrier rod 2 may again be operated as a main silk carrier, without disturbing the lever 52 which will continue to be held in its inoperative position by the member 46, and the stroke of the rod 2 will be controlled by the end stops 37 of the heads N, Figs. 1, 8 and 13. The lift member 49, and the rest member 46, are aligned with adjacent lower portions of the lock lever 52, so that the latter may be positioned by the member 46 to permit the travel therebeneath of the lift member 49. In like manner, the member 46 may be positioned beneath the lock lever 52, while the latter is supported by the lift member 49, without disturbing the position of the latter. Figs. 7a and 17 indicate how a portion 50 of the member 46 on the carrier rod 1 laterally overhangs the member 2a on the carrier rod 2, in effecting the above-described operations.

The device is particularly adapted for operation in an automatic full fashioned knitting machine. Thus, when the carrier rod 1 is automatically placed into operation, from the rest position of Figs. 8 and 13 to the operative position of Fig. 6, the support 46 is removed from under the lever 52, as indicated. The spring 47 lowers the lever 52 so that the contact member 52b will be in the path of movement of stop 2a to reduce the length of the stroke of the carrier rod 2 from that required while the rod is oper-

ating as the main silk carrier, to the length of stroke necessary for operation of the rod as a plating carrier.

The improvements specifically shown and described, by which the above results are obtained, are adapted to automatic, or semi-automatic, full fashioned knitting machines, and may be changed in various ways without departing from the invention as herein set forth and claimed.

10 I claim:

1. In a knitting machine, the combination with knitting mechanism including needles, reciprocable carrier rods having yarn carriers thereon for laying yarn to the needles, and means for reciprocating the carrier rods, of carrier rod stop means, and carrier rod operated means including elements carried by each of a plurality of the carrier rods and cooperating with said stop means for affecting the operation of a carrier rod by said reciprocating means to operate through strokes of different lengths.

2. A flat knitting machine comprising knitting mechanism including a needle bank, longitudinally reciprocable rods, means for reciprocating the rods, a carrier on one of said rods for laying yarn to said bank, and means including elements on said rods and stop means controlled by said one rod and by another of said rods for controlling said one rod to operate through strokes of different lengths.

3. In a knitting machine, in combination with the carrier rods thereof; means for varying the extents of longitudinal reciprocable movements of one yarn carrier rod, comprising a support, a stop mounted on said support for movement relative thereto in one direction between a position for stopping, and a position for releasing, said one rod, an element carried by said one rod responsive to movement thereof in the direction opposite to the one in which said stop is operative for moving said stop from said stopping position to said releasing position, and a member carried by another of said rods for holding said stop in said releasing position.

4. In a full fashioned hosiery knitting machine, in combination with the carrier rods thereof and drive means for imparting stroke movements to said rods; of carrier rod stop means controlled by and actuated by certain of said carrier rods for coacting with one of said rods to vary the extents of travel imparted thereto by said drive means to at one time have stroke movement of given length and at another time to have stroke movement of a length different from said given length.

5. A flat knitting machine comprising knitting mechanism including a needle bank, carriers for laying yarn to said bank, longitudinally reciprocable carrier rods for said yarn carriers, friction box means for reciprocating the rods, and means including elements on said rods and stop means controlled by a plurality of the carrier rods for affecting the operation of one of the rods as effected by said friction box means to operate through strokes of different lengths.

6. A flat knitting machine comprising knitting mechanism including a needle bank, carriers for laying yarn to said bank, longitudinally reciprocable carrier rods for said yarn carriers, friction box means for reciprocating the rods, stop means for affecting the operation of a carrier rod as effected by said friction box means to operate through strokes of different lengths, and means including elements on said rods and responsive only to a movement of one rod in the

direction opposite to the one in which a stop is operative for putting the stop out of action.

7. A flat knitting machine comprising a pair of parallel adjacent longitudinally reciprocable elongated yarn carrier rods, a stationary support between the ends of the rods, a stop for one of the rods movably mounted on the support for movement between positions, respectively, for stopping and releasing said one rod, an element on said one rod arranged to lift the stop from stopping to releasing position upon a movement of said one rod in the direction opposite to the one in which said stop is operative, and an element on the other rod upon which the stop rests in a given position of the other rod.

8. A flat knitting machine comprising knitting mechanism including a needle bank, carriers for laying yarn to said bank, longitudinally reciprocable carrier rods for said yarn carriers, means for reciprocating the rods, stop means pivoted to swing in a plane, extending vertically through the longitudinal axis of the rod on which it acts, and means including elements on said rods and stop means for affecting the operation of a carrier rod by said rod reciprocating means to operate through strokes of different lengths.

9. Means for varying the extents of longitudinal reciprocable movements of one of a plurality of yarn carrier rods of a knitting machine, comprising a support, a stop-backing member, a stop pivoted on said support for movement in one direction between a position backed by said member for stopping, and a position for releasing, said one rod, an element on said one rod responsive to movement thereof in the opposite direction for moving said stop from said stopping position to said releasing position, and a member on another of said rods for holding said stop in said releasing position.

10. A flat knitting machine comprising a pair of parallel adjacent longitudinally reciprocable elongated yarn carrier rods, a stationary support between the ends of the rods, a stop for one of the rods movably mounted on the support for movement between positions, respectively, for stopping and releasing said one rod, an element on said one rod for lifting the stop from stopping to releasing position, and an element on the other rod upon which the stop rests in a given position of the other rod.

11. A flat knitting machine comprising a pair of parallel adjacent longitudinally reciprocable elongated yarn carrier rods, a support bracket extending transversely to the rods adjacent thereto between the ends thereof, a stop for one of the rods pivotally mounted on the support bracket about an axis transverse to the rods for movement between a position against the support bracket to stop said one rod and a position to release said one rod, an element on said one rod for lifting the stop from stopping to releasing position, and an element on the other rod upon which the stop rests in a given position of the other rod.

12. A flat knitting machine comprising a pair of parallel adjacent longitudinally reciprocable elongated yarn carrier rods, a stationary support between the ends of the rods, a stop for one of the rods movably mounted on the support for movement between positions, respectively, for stopping and releasing said one rod, the stop being biased toward its stopping position, an element on said one rod for lifting the stop against said bias from stopping to releasing position, and an element on the other rod upon which the stop rests in a given position of the other rod.

13. A flat knitting machine comprising a pair of parallel adjacent longitudinally reciprocable elongated yarn carrier rods, a stationary support between the ends of the rods, a stop for one of the rods movably mounted on the support for movement between positions, respectively, for stopping and releasing said one rod, means including a spring for biasing the stop toward its stopping position, an element on said one rod for lifting the stop against the action of the spring from stopping to releasing position, and an element on the other rod upon which the stop rests in a given position of the other rod.
14. A flat knitting machine comprising a pair of parallel adjacent longitudinally reciprocable elongated yarn carrier rods, a stationary support bracket extending transversely to the rods adjacent thereto between the ends thereof, a stop for one of the rods pivotally mounted on the bracket about an axis transverse to the rods for movement between a position against the bracket to stop said one rod and a position to release said one rod, the stop being biased toward said stop position against the bracket, an element on said one rod for lifting the stop against said bias from stopping to releasing position, and an element on the other rod upon which the stop rests in a given position of the other rod.
15. A flat knitting machine comprising a pair of parallel adjacent longitudinally reciprocable elongated yarn carrier rods, a stationary support between the ends of the rods, a stop for one of the rods movably mounted on the support for movement between a position against the support to stop said one rod and a position to release said one rod, an element on said one rod for lifting the stop from stopping to releasing position, and an element on the other rod upon which the stop rests in a given position of the other rod.
16. A flat knitting machine comprising a plurality of reciprocable yarn carrier rods, a stop carried by one of the rods, a stop lever for cooperation with said stop to limit the stroke of said one rod, a member carried by said one rod to move said stop lever to inoperative position relative to said stop, and a member carried by an adjacent carrier rod for holding said stop lever in inoperative position to provide for unrestricted reciprocation of said one rod relative to said stop lever.
17. A flat knitting machine comprising a plurality of reciprocable yarn carrier rods, a stop carried by one of the rods, a pivoted stop lever swingable into and out of the path of movement
- of said stop, a lifting element carried by said one rod for swinging said stop lever to inoperative position, and a member carried by an adjacent carrier rod for holding said stop lever in said position to provide for reciprocation of said one rod past the position of said stop.
18. A full fashioned stocking knitting machine comprising a plurality of reciprocable yarn carrier rods, a stop carried by one of the rods, a pivoted stop lever swingable into and out of the path of travel of said stop, a lifting element carried by said one rod for moving said stop lever to inoperative position upon removal of said one rod from the knitting field, and a member carried by an adjacent rod for holding said stop lever in inoperative position when said second carrier rod is in inoperative position.
19. A full fashioned stocking knitting machine comprising a plurality of reciprocable yarn carrier rods, a stop carried by one of said rods, a pivoted stop lever swingable into and out of the path of movement of said stop, a lifting element carried by said one rod for moving said stop lever to inoperative position upon the removal of said one rod from the knitting field, and a support carried by an adjacent rod for maintaining said stop lever in its inoperative position during the movement of said second rod to inoperative position to provide for unrestricted reciprocation of said first carrier relative to said stop lever.
20. A flat knitting machine comprising a plurality of parallel adjacent longitudinally reciprocable elongated yarn carrier rods, a stationary support bracket having a portion extending transversely to the rods adjacent thereto between the ends thereof, a shaft supported by the bracket parallel to said transverse bracket portion thereabove, stops including one for each rod pivoted on said shaft, each of certain of said stops including a handle at one end and an adjustable contact element at its other end and being movable between operative and inoperative positions against said transverse bracket portion, respectively, at opposite sides thereof, a spring extending between the bracket and one of the stops for biasing the latter against said transverse bracket portion, an element on the rod corresponding to the spring biased stop for lifting the stop against the spring bias from stopping to releasing position, and an element on another of the rods upon which the spring biased stop rests in a given position of said other rod.

RUDOLPH ANKE.
